REFRIGERATOR

Filed June 13, 1927

Inventor
Harry S. Cleveland
By his Attorneys
Mervin and Pilson

UNITED STATES PATENT OFFICE.

HARRY S. CLEVELAND, OF MINNEAPOLIS, MINNESOTA.

REFRIGERATOR.

Application filed June 13, 1927. Serial No. 198,840.

My present invention provides an improved refrigerator, and, generally stated, the invention consists of the novel devices, combinations of devices and arrangement of parts hereinafter described and defined in the claims. In the accompanying drawings, which illustrate my invention, several forms or embodiments of the invention are illustrated.

10 Referring to the drawings, wherein like characters indicate like parts throughout the several views:

Fig. 1 is a transverse vertical section taken through a refrigerator of the so-called "side icing" type;

15 Fig. 2 is a front-to-rear vertical section taken through the refrigerator on the line 2—2 of Fig. 1;

Fig. 3 is a horizontal section taken through 20 the refrigerator on the line 3—3 of Fig. 2;

Fig. 4 is a front-to-rear section with some parts broken away, showing a refrigerator of the so-called "top-icing" type, involving 25 my invention; and

Fig. 5 is a horizontal section taken on the line 5—5 of Fig. 4.

Describing first the construction illustrated in Figs. 1, 2 and 3, the numeral 6 indicates the refrigerator casing provided at 30 one side of its upper portion with an ice chamber 7, below said ice chamber with a food compartment 8, and at the opposite side of the refrigerator with a food compartment 9 that extends from bottom to top of the 35 casing, and, in practice, will be provided with perforated shelves 10 indicated by dotted lines only in Fig. 1. The vertical partition 11 that divides the interior of the casing into the compartments or chambers

40 7, 8 and 9 terminates above the bottom of the casing to afford a large air passage 12 and terminates below the top of the casing to afford a free air-return passage 13. The

45 upper portion of the partition 11 forms the inside wall of the ice compartment, and this wall, as well as the top and side walls of the ice compartment, are lined with heavy layers of insulating material 14. This insulating material 14 is in addition to the ordinary insulating material applied throughout the top, bottom and side walls of the main casing, and preferably this additional insulating material 14 is exposed, that is, is not covered with either metal or wood, but

50 may be waterproofed, painted or enameled. The vertical side walls of the ice compartment

ment should be provided with metallic guard strips or cleats 15 that prevent the ice *y* from coming into direct contact with the exposed insulation. The ice is placed on a suitable 60 rack 16, which, in turn, rests on a metallic pan or bottom plate 17 that forms the top layer of the bottom 18 of the ice compartment.

Opening through the bottom 18 of the ice 65 compartment is a large cold air passage 19, which, as shown, extends a little less than from front to rear of the ice compartment, but might be extended completely from front to rear thereof. Preferably, this cold air 70 passage 19 is through an elongated metal sleeve 20 that is set through the bottom of the ice compartment and extends slightly above the pan 18 so as to prevent the ice water from running through the said cold 75 air passage. Of course, the melted ice may be carried off by the customary drain pipe, not shown. Secured to the bottom 18 of the ice compartment and extended below the cold air passage 19 and toward the left-hand 80 side wall of the casing, that is, away from the main food compartment 9, is a curved deflector 21. Applied to the top of the ice compartment in a position to overly the cake of ice is a curved deflector 22 that is 85 preferably hinged at 23, so that it may be raised when a large piece of ice is being placed in the ice compartment. The ice compartment 7 is shown as provided with the customary front opening door 24, the food 90 compartment 8 is shown as provided with the customary door 25, and the main food compartment 9 is provided with the customary front opening door 26.

To facilitate the circulation of air, the casing is shown as provided at its two lower corners with curved fillets 27 and 28, and at its upper right-hand corner with a larger fillet 29.

With the refrigerator constructed as described, the cold air will be precipitated 100 from the ice chamber through the cold air passage 19 and, by the deflector 21, will be directed toward the left-hand side of the chamber 8 and from thence will be caused to 105 flow downward along the left-hand side of said chamber to the bottom thereof, and from thence through the lower air passage 12, thence upward through the main food compartment 9, and thence through the 110 return air passage 13 to the top of the ice chamber 7. The air coming through the

return passage 13 into the top of the ice chamber will flow over the ice cake and as it travel forward the left-hand side of said ice chamber will be intercepted by the deflector 22, with the result that the air will be caused to strike first and chiefly upon the top of the ice cake and from thence downward around the sides thereof. Even when the ice cake is small or is low, the deflector 22 turns the return air downward onto the ice and prevents the same from flowing to too great an extent completely over the ice cake and down the left-hand side thereof. This improved circulation gives a rapid cooling of the air by causing the moisture of the air to condense immediately upon striking the ice, and consequently maintains relatively dry cold air evenly distributing throughout all parts of the food compartments. The additional insulating provided on the walls of the ice chamber reduces to a minimum the loss of temperature through the walls of the casing and practically stops all radiation of heat through the inside wall of the ice compartment.

In the modified construction illustrated in Figs. 4 and 5, the ice compartment 7^a of the casing 6^a is located immediately above the main and only food provision chamber 9^a. Said compartments 7^a and 9^a are provided with the customary doors, not shown. The cold air passage 19^a, as in the previously described structure, is extended through the central portion of the bottom 18^a of the ice chamber, and the curved deflector 21^a is secured to said bottom below said cold air passage. The air return passage 13^a, in this arrangement, is extended through the bottom 18^a close to the right-hand side of the casing, that is, through that side of the casing that is away from the side toward which the downwardly moving cold air will be deflected by the deflector 21^a. The numeral 10^a, Fig. 4, indicates perforated shelves located in the compartment 9^a. Again, in this structure, Fig. 4, the curved deflector 22^a is pivoted at 23^a to the top of the ice compartment.

The circulation of the air in the structure just described in connection with Figs. 4 and

5 is thought to be obvious from the description hitherto given of the circulation of the air in the refrigerator illustrated in Figs. 1, 2 and 3.

My invention herein disclosed is especially adapted for incorporation in small-size refrigerators, such as used in apartment houses, for example, where economy in space, as well as high efficiency, is highly important.

55

60

What I claim is:

1. A refrigerator having ice and food compartments connected by air-circulating passages, a cold air discharge passage located in the bottom of said ice compartment, and a downwardly concave curved deflector applied to the bottom of said ice compartment and extended under said cold air discharge passage and across the full depth of the inside of the food compartment for deflecting the air toward one side of the underlying food compartment.

65

70

2. A refrigerator having ice and food compartments connected by air-circulating passages, one of which is in the bottom of said ice compartment, a deflector applied at the top of said ice compartment for deflecting downward the air returned into the upper portion of said ice compartment, and which deflector is hinged so that it may be moved upward to clear large pieces of ice.

75

80

3. A refrigerator having ice and food compartments with air-circulating passages connecting the same, one of said air passages being a cold air discharge passage located in the bottom of said ice compartment, a deflector secured to the bottom of said ice compartment and extended under said cold air discharge passage for deflecting the downwardly moving cold air toward one side of the underlying food compartment, a deflector at the top of said ice compartment arranged to downwardly deflect the returning air, which moves toward that side of the refrigerator towards which the air is deflected by said lower deflector, and which upper deflector is hinged so that it is free to move vertically to clear large pieces of ice.
